EUGENE W. VOGEL, OF OAK PARK, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

HIGHWAY SIGNALING APPARATUS FOR RAILROAD SERVICE.

1,250,250.

Specification of Letters Patent. Patented Dec. 18, 1917.

Application filed June 5, 1914. Serial No. 843,226.

To all whom it may concern:

Be it known that I, EUGENE W. VOGEL, a citizen of the United States, residing at Oak Park, in the county of Cook and State of Illinois, have invented certain new and useful Improvements in Highway Signaling Apparatus for Railroad Service, of which the following is a specification.

My invention relates to signaling apparatus for railroad or like service, and particularly to apparatus of the type used at grade crossings for giving notice of the approach of a train, devices of this type being commonly called highway signal bells.

One of the principal objects of the invention is to provide a highway signal bell which will automatically start ringing on the approach of a train and will continue to ring for a predetermined time and then cease. A highway bell of this sort may be used with considerable advantage where the highway which it serves is located near a station. The ordinary highway signal bell operated from the track circuit will commence to ring as soon as the wheels of the train short circuit the track circuit battery and will continue to ring until the train leaves the section of track comprised by the track circuit. Therefore, if the highway is near a station where trains, particularly freight trains, are likely to be standing or switching for some little time, it will happen that the signal bell will ring for considerable periods at a time. This is objectionable for reasons of economy in the operation and up-keep of the apparatus, and more so because the public, becoming accustomed to hear the bell ring when there is no danger in making the crossing, will come, in time, to ignore the signal entirely. With the highway served by a device constructed in accordance with my present invention, the signal will cease after the lapse of a predetermined time from actuation, regardless of whether the train remains upon the adjacent portion of the track or not.

A further object of the invention is to so construct the apparatus that if the train has crossed the highway before the normal ringing period has elapsed, the bell will immediately cease ringing without waiting for the expiration of such period.

The invention has for further objects such

other new and improved constructions, arrangements and devices relating to railway 55 signaling apparatus and particularly to highway crossing bells as will be herein-after described and claimed.

The invention is illustrated, in certain preferred embodiments, in the accompanying 60 drawings wherein—

Figure 1 is a view, in elevation, of a highway crossing bell constructed in accordance with my invention, the bell and bell ringing mechanism mounted therein being 65 shown as swung away from the supporting disk or fixed housing member by means of which the apparatus is supported on a post, or like structure, the figure being somewhat 70 diagrammatic in its representation of certain parts of the apparatus and including a diagram illustrating the actuation of such apparatus by means of a line circuit opened and closed by the passage of trains over the track;

Fig. 2, a vertical sectional view of the apparatus;

Fig. 2^a, a detail sectional view showing a modified form of gasket;

Fig. 3, a view, in elevation, on an enlarged scale, of the bell and the ringing and controlling mechanisms in the same position in which these parts are shown in Fig. 1;

Fig. 4, a detail elevation, on a somewhat larger scale, of a part of the mechanism for 85 operating the signal;

Fig. 5, a sectional view taken on line 5—5 of Fig. 3;

Fig. 6, a detail view, in perspective, of the armature of what I have termed the controlling magnet, together with certain parts 90 associated therewith;

Fig. 6^a is a perspective view of the reverse side of portions of the structure shown in Fig. 6.

Fig. 7, a similar view of the structure supporting the controlling magnet and its armature;

Fig. 8, a similar view of an adjustable counterweight forming part of the controlling mechanism;

Figs. 9 and 10, detail views of contact springs employed for interrupting the current through the bell ringing magnet; and

Fig. 11, a diagrammatic view, similar in 105 its general character to Fig. 1, showing a

modified arrangement adapting the invention to be used in connection with the ordinary normally closed track circuit.

Like characters of reference designate like parts in the several figures of the drawings.

Referring first to Figs. 1 to 10 inclusive, A designates a railroad track used for traffic both ways, B a station, and C a highway crossed by said track adjacent the station B. 10 The highway signal of my present invention is shown as mounted upon a hollow post 25. The housing for the mechanism for operating the signal consists preferably of a disk or fixed member 26 secured to the post 25 by bolts 27 and a member 28 hinged to the disk 26. The disk 26 is formed with a pair of circumferential ribs 29, 30 between which is a gasket element 31 consisting preferably of a section of rubber tubing. The housing 15 member 28 is formed with a flange 32 overlapping the outer rib 29 and with a rib 33 which bears against the gasket 31. The bell 34 is secured by a screw bolt 35 to the housing member 28. A weather shield 35^a secured to a vertical flange 36 on the housing member 28, extends over the upper part of the bell. The bell clapper 37 is carried on a reciprocating rod 38 guided by a bracket 39 on the inside of the housing 28. The disk 26 20 is formed with an opening 40 for the wires constituting the electrical circuits through which the mechanisms to be hereinafter described are operated.

The bell ringing magnet 41, supported on 35 a bracket 42 on the casing member 28, is provided with a pivoted armature 43 to which is attached one end of an elastic member 44, the other end of the spring being loosely connected with an armature by a link 40 45. The clapper rod 38 is formed with an angular bend 46 which is held to the under side of the elastic member 44 by a keeper plate 47. A spiral spring 48 is interposed between the bracket 39 and an adjusting 45 screw 50 passing through the end of the horizontal portion 46 of the clapper rod. The function of the spring 48 is to assist the magnet 41 in raising the armature 43 and the parts associated therewith. The spring 50 is not intended to be strong enough to raise the armature by itself.

Secured to the pivoted end of the armature 43 is a bracket 51 carrying an insulating plug 52 on which rests the free end of a 55 contact spring 53, the other end of which is anchored to a stud 54 on a plate 55 secured to a block 56, of slate or other insulating material, by means of set screws 57 which pass through arcuate slots 58 in the plate 55 giving the latter capacity for angular adjustment. The contact spring 53 normally bears against a contact spring 59 secured to a plate 60 on the insulating block 56, the plate 60 being preferably formed with a 60 stop lug 61 which limits the upward move- 65

ment of spring 59. When the magnet 41 is energized the free end of the contact spring is raised and the contacts separated. This breaks the circuit through the magnet 41, as will be hereinafter described, deenergizing 70 the magnet and causing the armature to drop. The latter movement closes the circuit again by bringing contact springs 53, 59 together. The bell will begin to ring as soon as the circuit comprising the contact 75 springs 53, 59 is connected with the battery D (Fig. 1). It will continue ringing until its circuit is disconnected from the battery circuit. These operations are effected by means of a controlling magnet 62, the circuit through which is governed by circuit closing devices E, F and G operated by the trains (Fig. 1) and by certain timing mechanism which will be hereinafter described. The circuit closing devices E and G are 80 arranged on opposite sides of the highway at any suitable distance therefrom. Their function is to start the bell ringing, the device E operating when the train moves from left to right (Fig. 1) and the device G when 85 the train moves from right to left. The circuit through these devices is normally open. The circuit closing device F is normally closed and is arranged close to the highway. Its function is to stop the operation of the 90 bell as soon as the train has passed the highway. The timing mechanism, to be hereafter described, operates to keep the bell ringing for a certain predetermined time after actuation through the track device E 100 or G, as the case may be. The completion of the period, however, is conditioned upon the train not passing the track device F. As soon as the train reaches this point on the track the bell stops ringing even if the normal ringing period has not elapsed.

The controlling magnet 62 is supported on a bracket 63 (Fig. 7) secured to the upper edge of the insulating block 56 and provided with an armature 64 (Fig. 6) to which is 110 secured a brass plate 65 formed with lugs 66, 67, the structure being pivoted to the bracket 63 by means of a pivot pin 68 which passes through the lugs 66, 67 and is supported in a vertical plate 69 forming a part 115 of bracket 63 and a lug 70 on an arm 71 projecting from plate 69. The devices E and G, which may be any suitable form of circuit closing devices adapted to be closed by the presence of a train on the track A at the places where they are respectively located, are connected by a circuit consisting of wires 72, 73. When one of these devices is closed the magnet 62 is energized from battery D through a circuit made up as follows: a wire 74 leading from the battery D to a binding post 75 on the plate 55; a wire 76 from the binding post 75 to the magnet 62; a wire 77 from the magnet to a binding post 78 on a plate 79, a spring contact finger 120 125 130

80 secured to an upright 81 formed on the plate 79, a binding post 82 against which the contact finger 80 normally bears, a wire 83 connected with the wire 72, the track device 5 E or G, as the case may be, the wire 73 and a wire 84 from the wire 73 to the battery.

Closing of either of the devices E or G establishes in addition the circuit, which is a shunt from the circuit just described, 10 through the bell ringing magnet 41 as follows: from the binding post 75 through the spring contact 53, the spring contact 59, a wire 85 to magnet 41, a wire 86 from the magnet to a binding post 87, through a connecting strip 88 on which binding posts 87, 82 are mounted, to binding post 82 which is in the previously described circuit.

It will be understood that the controlling circuit through magnet 62 remains closed at 20 E or G only momentarily or as long as it may take the train to pass the point at which the circuit closing device in question is located. In order to maintain the energization of the magnet 62 for a definite 25 period of time, the movement of the armature 64 toward magnet 62 brings a spring contact finger 89 and binding post 90 together, thereby closing the circuit through the magnet, shunting out the track device 30 E or G. The contact finger 89 is secured to a pair of insulating blocks 91 on the plate 65. The binding post 90 is connected by a wire 92 with the normally closed circuit breaking device F. The latter is connected 35 by a wire 93 with the wire 73. With the spring finger 89 in contact with binding post 90 the circuit through the magnet is as follows: from battery D to magnet 62 through wires 74 and 76; to binding post 82 through 40 wire 77 and contact finger 80; from binding post 82 through a wire 94 to the contact finger 89; from binding post 90 through wire 92, circuit breaking device F and wires 93, 73 and 84 to the battery.

45 The circuit just described may be opened at F, which occurs when a train crosses the highway C, or by a separation between the contact finger 80 and binding post 82. This separation is brought about at the expiration 50 of a predetermined period after the signaling apparatus is first actuated through the instrumentality of the track device E by the following mechanism: The spring arm 44 carried by armature 43 of the bell ringing magnet is formed with an angular bend 55 terminating in a lip 96 adapted to bear upon an adjustable stop screw 97 carried in a bracket 98 secured to the insulating block 56, and a pawl 99 is secured to the 60 vertical portion 95 of the spring arm. The pawl engages a toothed wheel 100 journaled on a pin 101 supported by the plate 69 forming a part of bracket 63 and a depending angular member 102 forming part of the 65 same structure. The toothed wheel 100 is

formed with a hub 103 provided at its extremity with a snail cam 104 adapted to engage with a lug 105 on a pawl carrier 106 pivotally mounted on the pivot pin 68 sustaining the armature of the controlling magnet 62 and carrying a pawl 107 which operates upon a toothed wheel 108. This wheel turns on a pivot pin 109 between a boss 110 on the plate 64 and the angular portion 102 of bracket 63. The movement downward 75 of the arm 106 is limited by a stop 111 formed on a lug 66 of the plate 65. The arm is normally pressed against the stop lug by a leaf spring 112. Pivotally mounted on the same pivot pin 68 is a dog 113 which 80 engages the notched wheel 108. Spring 112 is bifurcated and one portion, 114, of it bears upon the dog 113 normally pressing the same against stop lug 111. A disk 115 formed with a weight 116 is secured to the 85 notched wheel 108 by means of set screws 117 which pass through an arcuate slot 118 in the disk.

The upward movement of the pawl carrier 106 is limited by a stop screw 119. The 90 notched wheel 100 is kept from reverse rotation by a dog 120 pressed against the wheel by a leaf spring 121. On the back of the notched wheel 108 is a fixed cylindrical block 122 of insulating material adapted 95 to come into contact with the spring contact finger 80.

The operation of the timing mechanism above described is as follows: When the armature 43 of the bell ringing magnet 41 is 100 raised, pawl 99 engages with notched wheel 100 and turns it a certain angular distance. At each complete revolution of the notched wheel 100 the pawl carrying arm 106 is raised by cam 104 and then allowed to 105 drop. As it drops the pawl 107 engages the notched wheel 108 giving it a partial rotation. The dog 113, which is independent of the arm 106, keeps the wheel 108 from turning back. As soon as the notched wheel 110 108 has been rotated far enough to bring the insulating block 122 against the spring contact finger 80 so as to separate the finger from the binding post 82, the circuit through magnet 62 is interrupted and the armature 115 64 falls backward lifting the dog 113 and the pawl 107 out of contact with the notched wheel 108. The weight 116 on the disk 115 secured to the face of the notched wheel 108 returns the wheel to its normal position. 120 By adjusting the angular position of disk 115 with reference to the circuit breaking element, the time which will elapse between the energization of magnet 62 through the closing of its circuit at E and the breaking 125 of the circuit through the magnet at 80, 82, may be accurately determined. If the normal period of ringing be fixed at one minute the bell will be rung for one minute after the train passes E and then will automati- 130

cally stop. If, however, the train crosses the highway before this minute period elapses the circuit of magnet 62 will be broken at F and the ringing will cease immediately.

In Fig. 11 I have shown somewhat diagrammatically a modification of the apparatus to adapt it for actuation from track circuits instead of the line circuit as hereinabove described. In this figure, the track adjacent the station and highway is divided into two insulated sections H, H', the insulation 123 between the sections being approximately at the highway. The sections 15 H and H' are provided with batteries J and J', respectively, connected by wires 124, 125, 124', 125', with the opposite rails near the outer insulated joints 126, 126'. In circuit with the insulated sections H and H', respectively, are the magnets K, K', of an interlocking relay, the magnets being connected by wires 127, 128, 127', 128' with opposite rails at points near the middle insulation 123. The circuit through each insulated section, its battery and relay, is normally closed so that the armatures 129, 129' of the relays stand out of contact with the contact points 130, 130' of the circuit, to be hereinafter described, which controls the operation of the signal. When a train comes upon one of the insulated sections H or H' it short circuits the battery, deenergizing the corresponding relay and causing the controlling circuit to be closed. The mechanism for operating the signal in this form of the invention is the same as that previously described except in certain particulars which will be noted in tracing out the circuits through the apparatus which are as follows: If a train moves upon the section H from the left (Fig. 11) the magnet K will be deenergized, bringing the contact arm 129 against the contact point 130. This closes a circuit constituted as follows 45 (the reference numerals heretofore used being employed where there is an exact correspondence between the elements): wire 74 from battery D to binding post 75, wire 76 to the magnet 62, wire 131 from magnet 62 to binding post 87^a (corresponding in position to binding post 87 but not electrically connected with binding post 82) wire 132 to a wire 133 connecting the contact points 130, 130', contact arm 129, a wire 50 134 connecting the contact arms 129, 129', a wire 135 from contact arm 129' back to the battery.

This energizes the controlling magnet 62 and closes a shunt circuit through the bell ringing magnet 41 as follows: from binding post 75 through contact springs 53, 59 and wire 85 to magnet 41; from magnet 41 through wire 136 to the contact arm 86 carried by the armature of magnet 62, binding post 90 against which the contact arm

89 bears when magnet 62 is energized, through wire 137 to binding post 78 and through contact spring 80, binding post 82 and wire 138 to the return wire 135. This sets the bell in operation and the operation continues, provided the train remains upon the insulated section H, until the circuit breaking element 122 on the notched wheel 108 comes into contact with the spring 80 and breaks the bell operating circuit by moving the spring away from binding post 82.

If, before this period of normal ringing has elapsed, the train crosses the highway and thereby leaves the insulated section H, the track circuit through magnet K will be reestablished causing the magnet to attract its armature 129 and break the controlling circuit through the magnet 62 at 129. This causes the armature 64 of magnet 62 to drop back opening the bell operating circuit through magnet 41 at 90.

Similarly when a train moving in this other direction comes upon the block H', it causes K' to drop its armature and close the initial circuit through magnet 62 at 129', 130'. This energizes the magnet 62 and the same series of operation follows as are above referred to, causing the bell to ring until the train crosses the insulation between the blocks. The interlocking relation between the armatures 129, 129' (any suitable form of interlocking relay may be employed) prevents the presence on the block H' of the trains moving from left to right from reactivating the apparatus and vice versa. A different arrangement, with reference to the gasket between the fixed and the closed casing in which the operative parts of the mechanism are housed, is shown in Fig. 2^a. The disk 26^a is formed with a rib 29^a in which is formed a channel 29^b slightly narrower at the bottom than at the top. In this channel is fitted a compressible gasket 31^a, the outer face of which is flat but is compressed by the rib 33^a on the hinged casing 28^a when the latter is closed, as shown in the figure. The compression of the gasket forces rims or ears 33^b out over the rib 29^a as shown. These arrangements make the housing absolutely water and dust proof.

While I have described my invention in certain preferred embodiments, it will be understood that further modifications might be devised without departure from the principles of the invention. Therefore I do not wish to limit the invention to the exact constructions, arrangements and devices shown and described except so far as the same are specifically claimed in certain of the claims herein.

I claim:

1. In signaling apparatus of the character described, the combination with a bell and electrically operated bell ringing mecha-

nism, of mechanism for controlling the operation of the bell ringing mechanism comprising a pivoted element provided with a counterweight, means for rotating said element, a retaining device adapted to prevent the reverse rotation of said element, a magnet which when energized maintains said retaining device in operative position, and means operated by said rotating element for 10 opening the circuit through said magnet.

2. In signaling apparatus of the character described, the combination with a bell and electrically operated bell ringing mechanism, of mechanism for controlling the operation of the bell ringing mechanism comprising a pivoted element provided with a counterweight, means operated by said bell ringing mechanism for rotating said element, a retaining device adapted to prevent the 20 reverse rotation of said element, a magnet which when energized maintains said retaining device in operative position, and means operated by said rotating element for opening the circuit through said magnet.

25 3. In a signaling apparatus of the character described, the combination with a bell and electrically operated bell ringing mechanism, of mechanism for controlling the operation of the bell ringing mechanism comprising a pivoted element provided with a counterweight, means for rotating said element, a retaining device adapted to prevent the reverse rotation of said element, a magnet which when energized maintains said 30 retaining device in operative position, and means operated by said rotating element for opening the circuit through said magnet, said weight being adjustable on said rotating element to vary the normal ringing period of said apparatus.

4. In signaling apparatus of the character described, the combination with a bell and electrically operated bell ringing mechanism, of mechanism for controlling the operation 45 of the bell ringing mechanism comprising a ratchet wheel provided with a weight, a magnet which holds said dog in operative position, a circuit breaking device carried by said ratchet wheel for opening the circuit through said magnet, and mechanism operated by said bell ringing mechanism for rotating said ratchet wheel.

5. In signaling apparatus of the character 55 described, the combination with a bell and electrically operated bell ringing mechanism, of mechanism for controlling the operation of the bell ringing mechanism comprising a ratchet wheel provided with a weight, a dog to engage said wheel, a magnet which holds said dog in operative position, a circuit breaking device carried by said ratchet wheel for opening the circuit through said magnet, a pawl operated by the bell ringing mechanism, a ratchet wheel rotated by the

pawl, and a pawl, operated by said last named ratchet wheel, which engages with the first named ratchet wheel.

6. In signaling apparatus of the character described, the combination with an electrically operated signaling mechanism, of mechanism for controlling the operation of said signaling mechanism comprising a magnet, a pivoted armature for the magnet, a pawl operated by the signaling mechanism, 70 a ratchet wheel rotated by said pawl, a cam on said ratchet wheel, a pawl carrier operated by said cam, a pawl on said pawl carrier, a second ratchet wheel operated by said last named pawl and provided with a counterweight, a dog for said weighted ratchet wheel which is maintained in operative position when said magnet is energized, and a circuit breaking device on said weighted ratchet wheel adapted to break the circuit 75 through said magnet.

80 7. In signaling apparatus of the character described, the combination with an electrically operated signaling mechanism, of mechanism for controlling the operation of said signaling mechanism comprising a magnet, a pivoted armature for the magnet, a pawl operated by the signaling mechanism, a ratchet wheel rotated by said pawl, a cam on said ratchet wheel, a pawl carrier operated by said cam, a pawl on said pawl carrier, a second ratchet wheel operated by said last named pawl and provided with a counterweight, a dog for said weighted ratchet wheel which is maintained in operative position when said magnet is energized, and a circuit breaking device on said weighted ratchet wheel adapted to break the circuit 85 through said magnet, said weight being angularly adjustable on the ratchet wheel to 90 which it is attached, for the purpose described.

85 8. In signaling apparatus of the character described, the combination with an electrically operated signaling mechanism, of mechanism for controlling the operation of said signaling mechanism comprising a magnet, a pivoted armature for the magnet, a pawl operated by the signaling mechanism, a ratchet wheel rotated by said pawl, a cam on said ratchet wheel, a pawl carrier pivoted to said armature and operated by said cam, a pawl on said pawl carrier, a second ratchet wheel operated by said last named pawl and provided with a counterweight, a 100 dog pivoted to said armature which operatively engages said weighted ratchet wheel when said magnet is energized, and a circuit breaking device on said weighted ratchet wheel adapted to break the circuit through 105 said magnet.

9. In signaling apparatus of the character described, the combination with a bell, of a clapper for the same, a reciprocating rod on which said clapper is mounted, an electro- 110

magnet provided with an armature and with circuit breaking spring contacts for reciprocating said rod, and a spring attached to said armature which assists said magnet in 5 raising said armature.

10. In signaling apparatus of the character described, the combination with a bell, of a clapper for the same, a reciprocating rod on which said clapper is mounted, an electro-magnet provided with an armature and with circuit breaking spring contacts for reciprocating said rod, and an elastic spring member secured at one end to said armature with its free end attached to said rod. 10
15. 11. In signaling apparatus of the character described, the combination with a bell, of a clapper for the same, a reciprocating rod on which said clapper is mounted, an electro-magnet provided with an armature and with circuit breaking spring contacts for reciprocating said rod, an elastic spring member secured at one end to said armature with its free end attached to said rod, and a spring interposed between a stationary part 25 of said apparatus and said rod so as to assist the magnet in raising said armature.
12. In signaling apparatus of the character described, the combination with a bell, of a clapper for the same, a reciprocating rod on which said clapper is mounted, an electro-magnet provided with an armature and with circuit breaking spring contacts and means for pivoting said armature to said rod for reciprocating said rod, a pawl 30 carried by said armature, and mechanism operated by said pawl which is adapted to open the circuit of said bell ringing magnet after the bell has been rung for a certain period. 35
40. 13. In signaling apparatus of the character described, the combination with an electrically operated signaling mechanism, of mechanism for controlling the operation of said signaling mechanism comprising a magnet, a pivoted armature for the magnet, a pawl operated by the signaling mechanism, a ratchet wheel rotated by said pawl, a cam on said ratchet wheel, a pawl carrier pivoted to said armature and operated by said cam, a pawl on said pawl carrier, a second ratchet wheel operated by said last named pawl and provided with a counterweight, a dog pivoted to said armature which operatively engages said weighted ratchet wheel when 45 said magnet is energized, a circuit breaking device on said weighted ratchet wheel adapted to break the circuit through said magnet, a circuit closing device adapted to be operated to close the circuit through said magnet, a spring contact arm carried by said armature adapted to establish a circuit through said magnet when the magnet is energized, shunting out said circuit closing device, and a circuit breaking device adapted to be operated to open said last named 50 circuit. 55
50. 14. In signaling apparatus of the character described, the combination with a bell and electrically operated bell-ringing mechanism, of a controlling magnet, a circuit closer shunted across the bell circuit and operated by said magnet, a momentarily operated circuit-closing device for closing both the circuit through the bell and the magnet, a circuit-breaking device in circuit 55 with the magnet and timing mechanism operated by said bell-ringing mechanism for breaking the circuit through the magnet after a predetermined period of time. 60

65. 15. In signaling apparatus of the character described, the combination with a bell and electrically-operated bell-ringing mechanism, a circuit closer, a controlling magnet operating said circuit closer, a circuit shunted across the bell circuit, a device for open-

net, a pivoted armature for the magnet, a pawl operated by the signaling mechanism, a ratchet wheel rotated by said pawl, a cam on said ratchet wheel, a pawl carrier pivoted to said armature and operated by said cam, a pawl on said pawl carrier, a second ratchet wheel operated by said last named pawl and provided with a counterweight, a dog pivoted to said armature which operatively engages said weighted ratchet wheel when said magnet is energized, a circuit breaking device on said weighted ratchet wheel adapted to break the circuit through said magnet, a circuit closing device for closing the circuit through said magnet, and a spring contact arm carried by said armature adapted to establish a circuit through said magnet when the magnet is energized, shunting out said circuit closing device. 70 75 80

15. In signaling apparatus of the character described, the combination with an electrically operated signaling mechanism, of mechanism for controlling the operation of said signaling mechanism comprising a magnet, a pivoted armature for the magnet, a pawl operated by the signaling mechanism, a ratchet wheel rotated by said pawl, a cam on said ratchet wheel, a pawl carrier pivoted to said armature and operated by said cam, a pawl on said pawl carrier, a second ratchet wheel operated by said last named pawl and provided with a counterweight, a dog pivoted to said armature which operatively engages said weighted ratchet wheel when said magnet is energized, a circuit breaking device on said weighted ratchet wheel adapted to break the circuit through said magnet, a circuit closing device adapted to be operated to close the circuit through said magnet, a spring contact arm carried by said armature adapted to establish a circuit through said magnet when the magnet is energized, shunting out said circuit closing device, and a circuit breaking device adapted to be operated to open said last named 90 95 100 105 110 circuit. 115

16. In signaling apparatus of the character described, the combination with a bell and electrically operated bell-ringing mechanism, of a controlling magnet, a circuit closer shunted across the bell circuit and operated by said magnet, a momentarily operated circuit-closing device for closing both the circuit through the bell and the magnet, a circuit-breaking device in circuit 120 with the magnet and timing mechanism operated by said bell-ringing mechanism for breaking the circuit through the magnet after a predetermined period of time. 125

17. In a signaling apparatus of the character described, the combination with a bell and electrically-operated bell-ringing mechanism, a circuit closer, a controlling magnet operating said circuit closer, a circuit shunted across the bell circuit, a device for open-

ing said circuit, a momentarily operated circuit-closing device for closing the circuit through the bell and the circuit through the magnet and said device for opening the circuit, a normally closed circuit-breaking device in circuit with said magnet and with said bell, and a timing device operated by said bell-ringing device for operating said device for opening the circuit after a pre-
10 determined period of time.

18. In a signaling apparatus of the character described, the combination with a bell and electrically-operated mechanism for ringing the bell for a definite period of time,

having thereon a ratchet wheel, controlling 15 means for said mechanism comprising a magnet provided with an armature having a pawl thereon adapted to engage said ratchet wheel to prevent reverse movement of said wheel when the magnet is excited, 20 and to release said wheel when the magnet is deenergized to permit a reverse movement of said wheel.
